BY *A. E. Carlson*.
ATTORNEY

UNITED STATES PATENT OFFICE.

HARRY A. MARIL, OF MINNEAPOLIS, MINNESOTA.

GARMENT.

1,327,625.

Specification of Letters Patent. Patented Jan. 13, 1920.

Application filed September 8, 1919. Serial No. 322,381.

To all whom it may concern:

Be it known that I, HARRY A. MARIL, a citizen of the United States, residing at Minneapolis, in the county of Hennepin and

5 State of Minnesota, have invented certain new and useful Improvements in Garments, of which the following is a specification.

This invention relates to garments and the object is to provide an apron of simple 10 and economical construction yet practical and efficient as a garment. The invention is clearly shown in the accompanying drawing in which:

Figure 1 is a front view of the apron as it 15 appears when being worn on a person. Fig. 2 is substantially a rear view of the apron as seen in Fig. 1.

Referring to the drawing by reference numerals, 3 designates the main body portion of the garment which is provided at its bottom with two legs 4 which are cut away at their rear upper parts as shown in Fig. 2. Said body and leg portions continue in two side portions 5 up as far as the arms of 25 the wearer. Two shoulder straps 6 connect the rear upper corners 7 of said side portions 5 to the upper front part of the garment. A neck strap 8 is secured to the upper end of the garment and is adapted to be passed over the head of the wearer. Two 30 diagonal back straps 9 are sewed to and connect said shoulder and neck straps, as shown.

It will be noticed that the garment is 35 without buttons, hooks, clasps or buckles of any sort. It is worn over the clothes as an apron and can be put on very quickly, and still is to all practical purposes fully as serviceable as other more complicated working garments. A high slit 10 in the front 40 of the garment and the low cut design in the

rear allow for toilet accomplishments without necessarily removing the garment. The purpose of the side portions 5 and the straps 9 is to hold the garment in place on the 45 wearer when he is in a stooping position.

Having now fully shown and described my invention what I claim to be new and desire to protect by Letters Patent is:

1. A garment of the class described, consisting of a front apron portion having legs extending from the lower end thereof, side portions integral with said apron portion, shoulder straps having their respective ends secured to said apron and side portions, a 55 neck strap fixed to the upper end of said apron portion, diagonal back straps connecting said neck and shoulder straps. 60

2. A garment of the class described, consisting of a front apron portion, legs extending downwardly from said apron portion and being cut out in their upper rear parts at a point substantially below the crotch, shoulder loop straps secured at upper side positions to said apron portion, a 65 neck strap secured at the upper end of said apron portion, diagonal back straps connecting said shoulder and neck straps.

3. A garment of the class described, consisting of a front apron portion having legs 70 extending from the lower end thereof, side portions integral with said apron portion, an integrally formed shoulder strap on each side of the garment the same connecting an upper side corner of said apron portion to 75 the adjacent side portion, a neck strap centrally positioned and fixed to said apron portion, diagonal back straps each connecting one of said shoulder straps to said neck strap. 80

In testimony whereof I affix my signature.
HARRY A. MARIL.
